UNITED STATES PATENT OFFICE.

EUGENE R. CARICHOFF AND BENJAMIN W. JONES, OF SCHENECTADY, NEW YORK, AS-
SIGNORS TO GENERAL ELECTRIC COMPANY, A CORPORATION OF NEW YORK.

ELECTROMAGNETIC SWITCH.

Original application filed January 26, 1920, Serial No. 354,030. Renewed January 6, 1922, Serial No. 527,520. Divided and this application filed November 2, 1920, Serial No. 421,281. Renewed March 22, 1924.

To all whom it may concern:

Be it known that we, EUGENE R. CARICHOFF and BENJAMIN W. JONES, citizens of the United States, residing at Schenectady, 5 in the county of Schenectady, State of New York, have invented certain new and useful Improvements in Electromagnetic Switches, of which the following is a specification.

Our invention relates to improvements in electromagnetic switches and in particular to switches having two windings for controlling a switch member biased to one position, one of the windings effective to operate the switch to another position against its bias and the other winding for governing the return of the switch member to the biased position. The first winding may be termed the "pick-up" winding and the other winding the "drop-out" winding. One of the objects of our invention is to provide a switch of the character indicated in which the "pick-up" and "drop-out" value may be independently adjusted. This application is a division of our former and co-pending application, Serial No. 354,030, filed January 26, 1920, renewed January 6, 1922, Serial No. 527,520, in which we have fully disclosed our improved electromagnetic switch and have claimed an improved system of control for electric motors in which this switch is employed.

In carrying our invention into effect, we provide a single switch member which is biased to one position and controlled by means of a "pick-up" electromagnet and a "drop-out" electromagnet. The electromagnets have substantially independent magnetic structures and improved means is provided whereby the magnetic reluctance of the electromagnets may be independently adjusted or varied in order that the "pick-up" and "drop-out" values may be predetermined at will. In one form of our invention, each electromagnet is provided with an armature or other movable member carried by the switch member, and the position of each armature is adjustable with respect to the winding of its electromagnet independently of the armature for the other electromagnet.

For a better understanding of our invention, reference is had to the accompanying drawings, in which Fig. 1 is a side view of our improved electromagnetic switch; Fig. 2

is a plan view of the same; Fig. 3 is a simplified diagram of a system of motor control employing a plurality of our improved electromagnetic switches directly controlling the starting resistors of an electric motor; and Fig. 4 is a simplified diagram of a system of motor control in which a plurality of our improved electromagnetic switches are employed as normally open relays controlling the winding circuits of a plurality of contactors which control the starting resistors of an electric motor.

Referring to Figs. 1 and 2 of the drawings, our improved electromagnetic switch 20 comprises a stationary contact 24 and a movable contact 25. The movable contact 25 is connected to the pivoted and movable member 26, to which the armature 27 of the upper coil 28 is connected and to which the armature 29 of the lower coil 30 is also connected. The member 26 carrying the contact 25 is biased to the unattracted position, that in which the contacts 24 and 25 make engagement, by means of the spring 31. In this embodiment of our invention, the switch is shown as being normally closed, 20 but our invention is not limited thereto, as will be explained in connection with the arrangement of Fig. 4. The armature 27 is supported by a bolt 32 having a screw thread whereby the armature may be very nicely 25 adjusted with respect to the core 33 of the electromagnet of which the winding 28 forms a part. A friction member 34 having a certain amount of resiliency is provided for retaining the armature 27 in the position 30 to which it has been moved. The lower armature 29 is likewise mounted on a bolt 35 having a screw thread and a resilient friction device 36 for holding the armature in the position to which it has been adjusted 35 with respect to the core 37 of the electromagnet of which the winding 30 forms a part. It will be observed that the magnetic structure of the upper electromagnet is substantially independent of that of the lower 40 electromagnet and that the two electromagnets may be adjusted substantially independently of each other.

In the use of our invention, as diagrammatically illustrated in Fig. 3, the closing 45 of the manually operated switch 70 connects the motor to the source of supply with the resistors R¹¹, R¹² and R¹³ in the motor cir-

cuit to limit the current taken by the motor in starting. The closing of the switch 70 short circuits the "pick-up" winding 71 of the first electromagnetic switch and permits this switch to close its contacts responsively to the voltage drop across the resistor R^{11} . The closing of the first electromagnetic switch short circuits the "pick-up" winding 72 of the second electromagnetic switch and permits this switch to be closed responsively to the energization of the "drop-out" winding 73 which is energized responsively to the voltage drop across the resistor R^{12} . A certain time interval will be introduced in the closing of the switch by reason of the fact that the "pick-up" electromagnet has a certain attractive effect for an interval after its winding is short circuited. This time interval may be varied by varying the positions of the armature 29 on the bolt 35, since the nearer the armature to the core of the electromagnet, the longer the armature will be held by the magnetization after the coil is deenergized. The closing of the second electromagnetic switch likewise causes the third electromagnetic switch to close in accordance with its bias to the closed position responsively to the voltage drop across the resistor R^{13} . The opening of the switch 70 causes the opening of all of the electromagnetic resistance switches, since the lower or "pick-up" windings are all energized in multiple across the contacts of switch 70. The parts will then be in the positions shown in the drawing.

In the arrangement of Fig. 4, the electromagnetic switches or contactors which control the starting resistors are of the normally closed type, and the electromagnetic relays for controlling these starting contactors are of the normally open type. With the parts in the positions shown in the figure, the closing of the pilot switch 74 energizes the line contactor 75 to close and connect the motor to the source of supply with the starting resistors R^{14} , R^{15} and R^{16} included in the motor circuits to limit the current taken by the motor at starting. The closing of the line contactor 75 short circuits the "pick-up" winding 76 of the first relay and energizes the "drop-out" winding 77 of this relay responsively to the voltage drop across the resistor R^{11} . The winding 78 of the second relay will be energized responsively to the voltage drop across the resistor R^{14} , the winding 79 will be energized in accordance with the voltage drop across the resistor R^{15} , the winding 80 will be energized in accordance with the voltage drop across the resistor R^{14} and R^{15} , and the winding 81 will be energized in accordance with the voltage drop across the resistor R^{16} . It will be observed that with the manually operated disconnecting switch 82 closed and the line contactor 75 open, as shown in the drawing, the

relays controlling the resistance contactors are all energized to close their contacts against their bias to the open position, and the resistance contactors are energized to open their contacts against their bias to the closed position. When the current taken by the motor has decreased to the predetermined value, the energization of the winding 77 of the first relay will be such that this relay will be permitted to open its contacts in accordance with its bias to the open position, and thereby deenergize the winding of the resistance contactor 83, permitting this contactor to close its contacts to short circuit the resistor R^{14} and the winding 78 of the second relay. The windings of the resistance contactors 84 and 85 will be deenergized in succession to short circuit the resistors R^{15} and R^{16} in succession in a manner which will be obvious to those skilled in the art.

It will be observed that the magnetic structure of each of the two electromagnets of our improved electromagnetic switch is substantially independent of the other electromagnet, and that the flux path of each electromagnet may be varied independently of the flux path of the other electromagnet by varying the positions of the armatures with respect to the cores of the electromagnets. It will also be observed that the switch may be either of the normally open or the normally closed type, depending upon whether the movable switch contact 25 is adapted to complete an electric circuit when the movable switch member 26 is in its biased position or to interrupt a circuit when the switch member is in its biased position. In other words, the switch may be used to either interrupt an electric circuit when the "pick-up" winding is energized, or to make a circuit when this winding is energized.

The values at which the relays will open and close may be varied independently of each other, and this wide range of permissible adjustment makes the relay suitable for almost all kinds of service to which electric motors are applied. It will also be noted that the same relay and coils may be used for all sizes of motors of substantially the same voltage, thereby effecting a simplification and reduction of the cost of control equipments and necessitating the carrying of very few spare parts in stock. Since there are no interlocking contacts, a great many operating troubles are eliminated, the wiring is very simple, and less time and labor will be required in building a control equipment. The relays have no mechanical connection with the resistance contactors and may be located in any desirable place, or may be locked up away from unauthorized persons and away from dirt. The contact parts of the relay are vertical and will thus retain a minimum amount of dirt.

If the switch is of the normally closed

type as shown in Fig. 3, the switch is never called on to break a circuit and thus may be made quite simple and inexpensive, since the closing of a circuit is relatively simple as compared to breaking a circuit, especially an inductive circuit. Because of that fact, the movement of the switch contacts may be anything desired, and the pick-up and drop-out values of the switch may be adjusted without regard to the distance which separates the contacts when the switch is open. Because of the wide range of permissible adjustment, either one of the switch coils may be connected so as to assist in effecting the opening of the switch or be connected as the coil which governs the closing of the switch. Since both switch coils are deenergized after the switch closes, there is no tendency to open the switch or to diminish the pressure on the switch contacts due to the increase in current when the resistance is cut out.

A still further important advantage of our invention is that (referring to Fig. 3) in case any one of the resistance switches should "freeze," it would affect only that section of resistance and not cause the motor to be connected practically directly to the source. Thus, assume that the contact tips of the first switch are accidentally welded shut and the resistor R'' is short circuited. The second switch will have its coil 72 short circuited by the first switch, but the rush of current will be such that the voltage drop across the resistor R^{12} will energize the coil 73 to open the contacts of the second switch. The second switch will open in the usual way, but this switch will be maintained open until after the current has dropped to the predetermined value. After the second switch closes the third will close in the manner previously explained. The systems of motor control disclosed in Figs. 3 and 4 are broadly and specifically claimed in our said application, Serial No. 354,030, filed January 26, 1920, renewed January 6, 1922, Serial No. 527,520, of which the present application is a division, for the purpose of obtaining patent protection for the electromagnetic switch which is disclosed in Figs. 1 and 2 of the present application and which is employed in the systems as shown in Figs. 3 and 4.

In accordance with the provisions of the patent statutes, we have described the principle of operation of our invention, together with the apparatus which we now consider to represent the best embodiment thereof; but we desire to have it understood that the apparatus shown is only illustrative, and that the invention can be carried out by other means.

What we claim as new and desire to secure by Letters Patent of the United States is:

1. The combination in an electromagnetic switch, of a switch member biased to one position, two electromagnets jointly controlling the switch member, one for operating the same to another position against its bias to the first position and the other for magnetically holding the same in the other position and for governing its movement to its biased position, and means for governing the reluctance of the flux path of each electromagnet independently of the other electromagnet whereby the operations of the switch member from and to its biased position are independently governed. 70 75

2. The combination in an electric switch, of a movable switch member biased to one position, two electromagnets jointly controlling the same, one for operating the switch member to another position against its bias and the other for governing the operation of the same to the biased position, each electromagnet having a magnetic structure which is substantially independent of the other electromagnet and each magnetic structure having a separate independently adjustable member connected to the switch member. 80 85 90

3. The combination in an electric switch of a switch member, two electromagnets for jointly controlling the same, each electromagnet having an armature secured to the switch member and a magnetic structure substantially independent of the other electromagnet, and means for adjusting each armature independently of the other armature so as to vary the effect of one electromagnet independently of the other. 95 100

4. The combination in an electric switch of a switch member biased to one position, two electromagnets for controlling the same, one for moving the switch member to another position against its bias and the other for governing the movement of the switch member to its biased position, each electromagnet having a substantially independent magnet structure and a separate armature secured to the switch member for controlling the same, and means whereby the position of the armatures with respect to their corresponding magnet structures are independently varied so that the movements of the switch member to and from the biased position are adjusted independently of each other. 105 110 115

5. The combination in an electric switch of a switch member biased to one position, a "pick-up" electromagnet for controlling the movement of the switch member to another position against its bias and a "drop-out" electromagnet for governing the movement of the switch member to its biased position, each electromagnet having a substantially independent magnetic structure, the "pick-up" winding adapted to be short circuited so as to give the control of the 120 125 129

movement of the switch member to the biased position to the "drop-out" electromagnet after an interval of time, an armature for the "pick-up" electromagnet, means for varying the position of the said armature so as to vary the said time interval, an armature for the "drop-out" electromagnet, and means for varying the position of

the same so as to vary the value of current in the winding of the "drop-out" electromagnet at which the switch member will be permitted to return to the biased position. 10

In witness whereof, we have hereunto set our hands this 1st day of November 1920.

EUGENE R. CARICHOFF.
BENJAMIN W. JONES.
